UNITED STATES PATENT OFFICE.

JAMES HEFFERNAN, OF LEOMINSTER, ENGLAND.

ENHARMONIC MUSICAL INSTRUMENT.

No. 904,325.

Specification of Letters Patent.

Patented Nov. 17, 1908.

Application filed June 28, 1907. Serial No. 381,382.

To all whom it may concern:

Be it known that I, JAMES HEFFERNAN, a subject of His Majesty the King of Great Britain and Ireland, residing at 3 The Pleasance, Leominster, county of Hereford, England, have invented certain new and useful Improvements in Enharmonic Musical Instruments, of which the following is a specification, reference being had thereto in the accompanying drawings.

This invention has reference to an improvement in musical instruments, my said improvements being applicable principally to instruments such as the organ and piano-forte that are provided with a keyboard every key of which corresponds to a note of determinate pitch; and my improvements in their application to such an instrument have for object to enable a performer to obtain therefrom harmonies of more perfect concord and melodies of a juster intonation than have heretofore been obtainable from keyed instruments tuned to the usual equally tempered scale, this result being moreover obtained without undue complication of the keyboard or multiplicity of keys. These objects are in accordance with my invention attained by assuming as the basis of my scale, not the octave, as has heretofore been usual, but the interval usually known as the twelfth, corresponding to that between middle C and the G next but one above it, commonly called G in alt; and this interval is, in accordance with my invention, divided into twenty-four equal intervals, which, as a slightly tempered octave contains fifteen such intervals each nearly equal to half of a minor tone, are herein-after called quindecimal semitones, my improved scale being correspondingly called a quindecimal scale. A keyed musical instrument in accordance with my invention will consequently comprise fifteen keys in each octave instead of twelve keys as heretofore usual. As the musical notation usually employed is not well suited to an instrument provided with additional keys according to my invention, I have moreover devised for the same a simplified and improved notation as herein set forth.

In the accompanying drawings, Figure 1 is a diagrammatic representation of my first arrangement of keyboard corresponding to the quindecimal scale; Fig. 2 is a diagrammatic representation of a keyboard similar to the representation in Fig. 1, hav-

ing a compass of three octaves; Fig. 3 is a diagrammatic representation of a modified arrangement of a quindecimal keyboard; Figs. 4, 5 and 6 are illustrations of my improved quindecimal notation. Fig. 7 is a diagram illustrative of the tuning of an instrument to the quindecimal scale.

The names of intervals, as fifths, etc. when herein employed, have their ordinary meanings unless modified by the context.

The twelfth (mid. C to G in alt) has the ratio 1:3, and by taking logarithmically the 24th root of 3, the required quindecimal semitone is found. The building up of the major and minor thirds, the fifths, and other intervals is set forth in the following table of the quindecimal scale.

The common logarithm of 3 is 0.47712, and its 24th part is 0.01988, which is the logarithm of the quindecimal semitone. In the table it will be seen that this logarithm, by constant addition of itself, gives rise to a series of logarithms which, by means of a table of logarithms, are converted into absolute numbers. These numbers are then multiplied by 100 in order to get the vibration numbers of each interval with C taken at 100 vibrations per second. The approximation of the vibration numbers to those for just intonation is shown in the last column of the table by + (plus) for sharpness and - (minus) for flatness.

It will be noticed in the table that the minor third (C to E), the tenth (mid. C to E in the fourth space of treble clef) and the twelfth (mid. C to G in alt) are practically perfect. The major third (C to E) is only 0.56 per cent. too wide as compared with 0.79 per cent. too wide of the present (duodecimal) major third, to which the quindecimal interval is therefore much superior. The fifth (C to G) is 0.65 per cent. too sharp (wide) and the octave the same percentage too flat (narrow). I have carefully calculated (and practically verified it on my violin) that this sharpness of the fifth is practically equal to that always given to their fifths in the tuning of the strings of the violin by the violinists of a good orchestra. From these facts it follows, theoretically, that the major and minor triads of the quindecimal scale are almost perfect, and a great improvement on the triads of the ordinary (duodecimal) scale of 12 semitones to an octave, with its flat fifths, wider major thirds, and with its minor thirds the harmony of which is practi-

cally destroyed since in the ordinary (duo-decimal) tempered scale they are 0.90 per cent. too flat (narrow).

In the quindecimal scale

5	Each minor third is to consist of 4 semitones
	" major " " " " 5 "
	" fifth " to consist of 9 "
	" octave " " " 15 "
	" " " " 3 major thirds
	" " " " 3 minor thirds
	" twelfth " " " 24 semitones
10	" " " " 6 minor thirds
	" " " " 4 major thirds

The results are shown in the following

Table of the quindecimal scale.

35 In the last column of the above table the percentage deviation from just intonation is marked + or - according as the tuning of the quindecimal scale is sharp or flat with respect to just intonation.

The quindecimal scale has 15 separate and distinct keynotes to the octave. It contains a new consonance, C A $\sharp$, which has approximately the ratio 4:7 and the inclusion of which in the musical scale was suggested by the German physicist Helmholtz more than 30 years ago in his work, the "Sensation of Tone."

The semitone of the quindecimal scale borders upon, but does not transgress the ultimate limits of narrowness laid down by musicians, viz., $\frac{1}{4}$, or the difference between a major and a minor third; and by the adoption of this scale all concords are rendered more perfect, and all discords more definite than in the ordinary tempered scale of 12 semitones to an octave.

The quindecimal scale is applicable to all musical instruments whatever be the source or medium of vibration—string, wind, reed, plate, disk or fork. It is even applicable to instruments of the violin type, with properly adjusted lengths of strings and appropriate tuning.

65 Fig. 1 illustrates my first application of the

quindecimal scale, in major tones (of three quindecimal semitones each), and minor tones (of two quindecimal semitones each) and quindecimal semitones, in accordance with the vibration numbers of the table to the key- 70 boards of the organ, harmonium and piano-forte, and such like instruments. The long, thin lines show the white keys, and the short thick lines show the black keys and the semitones in a twelfth are numbered from 0 to 75

24. In the drawing the order of succession of the seven intervals in the key of C major is minor tone, major tone, quindecimal semitone; major tone (intervening); minor tone, major tone, quindecimal semitone and the 80 quindecimal semitone occurs between the 3rd and 4th, and between the 7th and 8th keys of the octave as in the ordinary scale of C major. I have found, however, that this arrangement is not suitable for the 85 quindecimal scale of 15 quindecimal semitones to the octave, for the following reasons. Referring to the table of vibrations, it will be seen that—the fifth C to G being too sharp (wide) by $\frac{1}{3}$ vibr. (.65) per 100 vibrations, and the octave, C to C, being too flat (narrow) by $\frac{1}{3}$ vib. (.65) per 100 vibrations—they both combine to give a fourth G to C, or its equivalent C to F, which is 1 $\frac{1}{3}$ vib. (1.3) per 100 vibrations too flat (narrow); and F is therefore out of tune with the tonic C. For this and other reasons—musical and mathematical—the key, F, must be relegated to the black keys. This leaves room for the quindecimal semitone to occur 100 in its proper place between Eb and E, the minor and major thirds above the tonic C. With the key F, there go out of the scale of the so-called major tone, F to G, and its 105 congener, D to E, both of them ever too wide, and yet wider with 3 quindecimal semitones, and both originally begotten of the difference between a fifth and a fourth. (Thus:—

C G—C F—F G in major mode, tonic C
A E—A D—D E, " minor " " A)

110 There only remains, within the compass of a fifth from the tonic, the quindecimal tone, C to D, whereupon to build. It is made up of 2 quindecimal semitones, and the next higher like interval is, D to Eb. There is then the quindecimal semitone, Eb to E, occurring in its proper place between the minor and major thirds from the tonic, Fig. 2. We thus have the major third built up of tone, 115 tone, quindecimal semitone:—

(1) C...D...Eb E.

From E, like synthesis proceeds to G by two 120 quindecimal tones, each of two quindecimal semitones, thus:—

(2) E...F $\sharp$ ...G.

Coinbining these two syntheses, we get

(3) C...D...Eb E...F $\sharp$ ...G (Fig. 2) 130

wherein the synthesis of the fifth by minor and major thirds is complete and symmetrical.

5 *Table of the intervals of the decade scale (white keys only.)*
 See Figs. 2 and 3.

Notes.	Name of Interval.	Number of quintooctonal sonitones.
10 C to C.	Unison.	0
C to D.	Second.	2
C to E $\flat$.	Minor third.	4
C to E.	Major third.	5
C to F $\sharp$.	Fourth (dissonant).	7
C to G.	Fifth.	9
C to A $\sharp$.	Minor sixth.	10
C to A $\sharp$.	Sharp sixth.	12 Helmholtz's consonance.
15 C to B.	Natural seventh.	14
C to C'.	Octava (by letters). Decade (by white keys).	16

When hereinafter I use the term decade,
20 as applied to the decade scale, it will be as
the equivalent of the term octave (ratio 1:2)
of the present scale.

It will be noticed that the major sixth C to A, although it is concordant with the tonic does not occur in the white keys of the decade scale in Fig. 2. A is a major third above F and thereby follows F into the black keys. This form of keyboard is very suitable for the organ, harmonium, piano-forte, and such like instruments. The long, light lines in Fig. 2 show the white keys, and the short, thick lines show the black keys, and the quindecimal semitones in a decade are numbered from 0 to 15. The decade is equally divided into three major thirds, and each major third is closed by the quindecimal semitone.

The advantages of the decade scale are as follows:—

40 (a) The practical perfection of the major and minor triads, *e. g.*, C E G and C E $\flat$ G.

(b) Through having F# in the white keys, midway between E and G, it bridges over the "break" (from F to G) that always occurs between the natural fourth and fifth of the human voice in our present scale.

(c) It combines the major and minor modes in one scale of 10 notes, whereby all relative minor keys are rendered unnecessary. For example, each of the notes, C, E, and A bears, in white keys only, both major and minor triads.

C E G, E A B, A B C E ... Major triads.
C E B G, E G B, A B E ... Minor triads.

55 (d) The succession of tone, tone, semi-tone, being repeated three times in the decade, C to C, the composer can think, and the performer can play in three tonics—viz., C, E and A $\flat$ —by using only white keys, i. e.
 60 without using accidental or black keys, unless the complexity of the theme requires them. The similarity of the arrangement of white keys of the scale of C to that of the cognate scales of E and A $\flat$ is indicated below the diagrammatic portion of Fig. 2.

(e) The succession of tones and quin-decimal semitones for the two cognate tonics E and A $\flat$, being therein shown with the same white keys as those for the key of C, it follows that the keys necessary for any tonic are only those required for two other cognate tonics, each a major third above the preceding one; and that, by learning the fingerings of the 5 keys—C, C $\sharp$ D, D $\sharp$ and E $\flat$ the performer can play in the tonic corresponding to any one of the 15 quin-decimal semitones of which the decade is made up. For instance the notes—white or black—used for the decade scale of

Tonic C	are identical with those for	E	and Ab	SC
" C#	"	F	A	
" D	"	F#	A#	
" D#	"	G#	B#	
" E	"	G	B	

By this means, the 30 different fingerings necessary for the 30 tonics, major and minor, at present in use (1 natural, 7 sharps, and 7 flats = 15, in both major and minor) are reduced to 5. Such are the advantages of the decade scale. 85

Now, by referring to the drawing of the 90 decade scale in Fig. 2, it will be seen that among the white keys of the decade scale, there are four, viz., E $\flat$, F $\sharp$, A $\flat$, and A $\sharp$ —to which I have been compelled to give their present accidental signatures, and that this 95 is not only confusing in the key of C, but would become worse in other keys, if our present mode of writing music were applied to the decade scale. It would, in fact, give rise to irremediable confusion in any score. 100 I obviate this difficulty by the following mode of writing music for the decade scale.

The five lines of the present treble clef and of the bass clef to be, each, replaced by a single line called the treble or bass clef-line according to its key-signature—the key signature of the bass clef line being uniformly two decades lower than that of the treble. The middle C of the pianoforte to be written simply C, and its decade keys above and below to be respectively written C', C² and C₂, C₃, and so on throughout the whole keyboard. No other letters are used on the lines. These clef-lines are to be written—not the literal notes nor black dots, but—the number of quindecimal semitones contained in the required interval as shown. For instance the triad C E G would be written in both notations as in Fig. 5 and the triad C E^b G in both notations as in Fig. 6 a fifth being always 9, a major third 5, and a minor third 4 quindecimal semitones above the tonic which is denoted by zero.

Leger lines above or below the treble or bass clef-lines are to be used for decades 12 above or below the literal key signature.

The numerals upon the clef-lines are to indicate the number of quindecimal semitones above the literal tonic, and the numerals below the clef-lines to indicate the number 13

of semitones above the lower decade note of the literal tonic. In Fig. 6 I give three decades, first in the ordinary notation, and then in the numerals of the semitones of the decade scale. From these three examples it will be seen that the numeral for the same interval is always constant. If, in the first example, I had written the tonic as C, there would be no need of a ledger line; and if, in the third example, I had written the tonic as C (instead of C₁) the numerals would be under instead of being upon the clef line. It will also be seen that the numerals will always be the same for the same interval no matter how the key-signature of the tonic may change. Otherwise stated, this means that by merely changing the key-signature of the clef-line, music, thus numerically written in quindecimal semitones, is at once transposed into another key.

Fig. 3 is given as an example of a keyboard in one of several possible forms in which the 15 quindecimal semitones of the interval C to C₁ may be arranged. The decade scale as shown in Fig. 2 herein and hereinafter described, is however, the most practicable and natural, and I therefore now more particularly describe the arrangement of the white and black finger-keys of the decade scale in Fig. 2 of the new keyboard for the organ, harmonium and pianoforte, by comparing it with the arrangement of the white and black notes of the keyboard in present use.

It will be noticed that the 10 white finger-keys of the decade scale in Fig. 2 cover the same interval, viz., C to C₁, as the 8 white finger-keys of the octave of the scale at present usually employed, and that there are 15 quindecimal semitones in the former, and 12 duodecimal semitones in the latter. Also, that there are in Fig. 2, 10 white and 6 black finger-keys instead of 8 white and 5 black finger-keys as heretofore usual.

The material, size, shape, mode of fitting, and working appliances of the keys in the keyboard of the new decade scale can be the same as any in use at present in the keyboards of the organ, harmonium and pianoforte; but the tuning and the arrangement of white and black finger-keys are to be different. The new tuning is hereafter described.

It will be noticed that the first six notes (white and black) of the decade scale in Fig. 2 (C to E), embrace two quindecimal tones and one quindecimal semitone, and that each of these two tones, viz. C to D and D to E_b, is divided into two quindecimal semitones by a black key, viz., C[#] and D[#] respectively and that the first six notes (C to E) embrace the interval of a major third divided into 5 quindecimal semitones. Also that the remainder of the decade scale is made up of other two major thirds, the sub-division of which is exactly similar to that of the first—the last note of each major third being the first note of

the major third next following. In fact the decade scale in Fig. 2 is made up of 3 major thirds each of which is similarly divided into three intervals the first and second of which contain two quindecimal semitones and the third a quindecimal semitone. In the decade scale, as shown in Fig. 2, the notes to which I have given the literal names of C[#] and A_b may also be respectively named D_b and G[#] if that should be convenient to the maker of the new keyboard.

Fig. 7 illustrates the mode of tuning a twelfth from middle C to G in alt. in 24 equal semitones or 6 minor thirds of 4 semitones each.

The procedure is as follows:—

(1) The first step is to tune a perfect twelfth (mid. C to G in alt.) which should be divided into 6 perfect minor thirds. The minor thirds should be tuned upwards from C and downwards from G as indicated by the arrows, and they should be quite equal and of perfect intonation—the one care of the tuner being that they are not in any degree too narrow like the tempered minor thirds of the ordinary scale of the pianoforte. The tuner will have three checks in the tuning of row (1)—see Fig. 7. First, the upward tuning from C and the downward tuning from G must both meet in A[#] giving perfect and equal minor thirds throughout. Second, the tonic C and E will give the perfect concord of the tenth (middle C to E in the fourth space of treble clef). Third, the same perfect concord of the tenth will be found between E_b and G. The tuning of the six perfect minor thirds in a twelfth in row (1) of Fig. 7 is the foundation of all that follows and cannot be too carefully performed.

(2) The next step is to tune G a sharp fifth above the tonic C as indicated by the arrow in Fig. 7. I have calculated this sharpness as 1 vib. per 100 vibr. (0.65 per cent. in table of vibrations) and I have also found that it is, mathematically, about equal to the degree of sharpness which is always given to their fifths in the tuning of the violinists of a good orchestra. In practice it is that degree of sharpness which gives the fifth brilliancy without roughness; and the exact amount of sharpness will, after a few trials, become familiar to the tuner's ear. From G the tuner will tune upwards and downwards by perfect minor thirds—same as in row (1)—as indicated by the arrows in Fig. 7. All the notes in row (2) can be checked by sounding each of them with the proper notes of row (1), and I have marked in row (2) of Fig. 7 with a double cross (x x) those which should give a rather flat (narrow) octave, and with a single cross (x) those which should give a sharp (violin) fifth with the corresponding notes of row (1). For instance in row (2) we have C[#] E and G which should be a rather narrow octave below C[#].

E and G of row (1). So also, in row (2), the notes B_b, D and F will be a sharp (violin) fifth above E_b, G_b and A_# of row (1). Besides these checks there is also the check of 5 the perfect tenth (i. e. twenty quindecimal semitones) which will always be found between the first and last notes of row (2)—C_# and F—and also between the first and last notes of the two following rows—i. e. row (3) 10 and row (4).

(3) The third and fourth steps of the tuning are exactly similar to the second. For instance, in row (3) the tuner tunes B a sharp (violin) fifth above E in row (2), and 15 the other notes in row (3) are got by perfect minor thirds, upwards and downwards from the B thus found. In row (3) the notes D and F are marked with a double cross (x x) to indicate that they can be checked as giving 20 narrow octaves with the D and F of row (2). So also, in row (3), the notes A_b, D_# and F_# are marked with a single cross (x) to show that they can be checked by their giving sharp (violin) fifths with C_#, G, and B_b 25 of row (2). Besides these three checks there is also the check of the perfect tenth (20 quindecimal semitones) between the first and last notes of row (3) viz. D and F_#.

(4) In the fourth (and final) step of the 30 tuning, A in row (4) is tuned a sharp (violin) fifth above D in row (3): and the other notes are tuned, as before, by perfect minor thirds, upwards and downwards from A. In row (4) the notes D_#, F_#, C, E_b and G_b are each 35 marked with a double cross (x x) for check

by giving a narrow octave with the notes D_# and F_# in row (3) and with C, E_b and G_b of row (1). There is also in row (4) the check of the perfect tenth (20 quindecimal semitones) between its first and last notes D_# 40 and G_b.

The tuner will remember that the sequence of successive fifths in the quindecimal scale is C, G, D_#, A_#, E_# (F) and B_# (C) as compared with C, G, D, A, E and B of the scale 45 at present in use.

What I claim is:—

1. In a musical instrument, a keyboard comprising keys, and sources of sound adapted to be operated by said keys and tuned in 50 such manner that the musical interval between any two successive keys is one twenty-fourth of the interval known as a twelfth.

2. In a musical instrument, a keyboard consisting of successive groups each comprising five keys whereof the first third and fifth keys are long, while the second and fourth keys are short, and a series of sources of sound adapted to be operated by said keys and so tuned that the musical interval 55 between any two adjacent members of said series is equal to one twenty-fourth of the interval commonly known as a twelfth.

In witness whereof I have hereunto set my hand in presence of two witnesses. 65

JAMES HEFFERNAN.

It is hereby certified that in Letters Patent No. 904,325, granted November 17, 1908, upon the application of James Heslerman, of Leominster, England, for an improvement in "Euharmonic Musical Instruments," an error appears in the printed specification requiring correction as follows: In lines 80-83, page 3, in the fourth line of the tabulation "G ♯" and "B ♯" should read *G_b* and *B_b*; and that the said Letters Patent should be read with this correction therein that the same may conform to the record of the case in the Patent Office.

Signed and sealed this 26th day of January, A. D., 1909.

[SEAL.]

C. C. BILLINGS,
Acting Commissioner of Patents.
